REFRIGERATING APPARATUS

Albert J. Kuhn, Dayton, Ohio, assignor to General Motors Corporation, Dayton, Ohio, a corporation of Delaware

Application July 30, 1940, Serial No. 348,409

4 Claims. (Cl. 290—38)

This invention relates to refrigerating apparatus and more particularly to automatic starting means for internal combustion engines used for driving refrigerator compressors and other applications wherein automatic starting is desired.

In automatic starting systems for internal combustion engines it is desirable to provide some means for stopping the starting motor in case the engine should fail to start. I have found that the means previously used for taking care of such a situation were not altogether accurate and reliable.

It is an object of my invention to provide an automatic starting system for an internal combustion engine which is accurate and reliable.

It is another object of my invention to provide a means for accurately and reliably deenergizing the starting motor of an internal combustion engine in case the engine fails to start within a reasonable time.

It is another object of my invention to provide an improved, more reliable and more accurate electrical timing device for limiting the time allowed for the starting motor to start an internal combustion engine.

Further objects and advantages of the present invention will be apparent from the following description, reference being had to the accompanying drawing, wherein a preferred form of the present invention is clearly shown.

In the drawing:

Fig. 1 is a wiring diagram of one form of an automatic starting system for an internal combustion engine embodying my invention;

Fig. 2 is a view in elevation of a vibrating type relay shown diagrammatically in Fig. 1; and

Fig. 3 is a wiring diagram illustrating another form of the invention.

Briefly I have shown an electrothermal timing device for limiting the energization of the starting motor of an internal combustion engine. The current operating this timing device is accurately controlled regardless of battery conditions so that the starting motor can only be energized for a predetermined length of time such as 30 seconds in case the engine fails to start. This regulation is so accomplished that in case the device fails to operate properly the time allowed will not be lengthened.

Referring now to the drawing and more particularly to Fig. 1, there is shown diagrammatically a starting motor 20 for starting an internal combustion engine through some suitable cranking device such as the Eclipse Bendix drive or the Dyer drive. The internal combustion en-

gine is preferably provided with some suitable ignition system of either the battery or magneto type. The internal combustion engine may be used to operate a refrigerant compressor, a motor car or any other suitable device.

The energization of the starting motor 20 is controlled by a switch means 22 closed by the energization of a solenoid 24 located in a parallel electrical circuit 25. The switch means 22 is connected by the conductor 26 to one terminal 30 of the battery 28 while the starting motor 20 itself is connected by the conductor 32 to the other terminal 34 of the battery 28. When the engine is used to drive a refrigerant compressor, the energization of the solenoid 24 is preferably controlled by a solenoid switch 36, controlled by a high pressure switch 38 operated in response to a predetermined high condenser pressure in the refrigerating system. This switch 36 is normally closed while the switch 38 is normally open. A second solenoid switch 40 is connected in series with the switch 36 and the solenoid 24 and is controlled by the thermostatic switch 42 which may be operated to energize and close the solenoid switch 40 upon a predetermined increase in temperature. This thermostatic switch 42 may be responsive to room or interior temperature, cabinet temperature or evaporator temperature.

In the systems shown there is no means for deenergizing the starting motor 20 when starting is accomplished. If desired, some switch responsive to the operation of the engine, such as a centrifugal switch, an oil pressure switch or a manifold vacuum switch may be connected in series with the switches 36 and 40 to open the solenoid switch 22 and deenergize the starting motor. However, even if such a switch is installed it is also desirable to provide a time limitation upon the operation of the starting motor 20 in case the motor fails to start. For this purpose I provide a switch means 44 which is operated by an electrothermal timing device connected in parallel circuit arrangement with the starting motor 20 and in series with its switch 22. The operating means for the switch 44 may be of any electrical type but for illustrative purposes it is shown diagrammatically as a cantilever type of bimetal 46 in operative connection by means of the rod 48 with the switch 44. This bimetal 46 is energized by an electric heater 50 at such a rate that when the starting motor 20 is operated for a predetermined period such as 30 seconds, the bimetal 46 will move the rod 48 to operate the switch 44 to deenergize the solenoid 24 and to connect in circuit a warning device 52, such

as a buzzer to indicate the failure of operation of the internal combustion engine.

In order that this timing be accurate and reliable, I have provided a regulating scheme for regulating the output of the heater under all battery conditions. To do this, I have connected a resistance 54 in series with the heater 50. In parallel with the heater 50 I have connected the solenoid 56 of a vibrating type control. The contacts operated by the armature 58 of this vibrating contact mechanism connect with the conductor 60 which is connected in parallel with the resistance 54 so as to shunt out resistance 54. A conductor 62 connects the armature 58 with the conductor connecting the heater 50 and the resistance 54.

This type of device accurately regulates the amount of current flowing through the heater 50 by the intermittent operation of the armature 58 which connects and disconnects from the conductor 60 so as to shunt the resistance 54 part of the time and otherwise require all the current to flow through the resistance 54. Thus by this device a measured amount of current will flow through the heater 50. This device, however, has a further advantage that in case of failure it will not increase the length of time the switch 44 remains closed. Normally, in this device, any failure would result in the sticking of the vibrating contacts so that the armature 58 would be connected to the conductor 60. This would decrease the time the starting motor 20 would be allowed to operate so that the protective device is assured of operation under practically all operating conditions.

Fig. 2 shows a practical embodiment of one form of a vibrating contact device. The coil 56 at all times exerts a magnetic attraction upon the armature 58. This attraction is opposed by the coil spring 64 which is connected to an extension 66 of the armature 58 on the opposite side of the spring hinge 68. The downward movement of the armature 58 is limited by the stop 70 while the upward movement is limited by the rubber stop 72. The armature 58 carries a contact 74 which is adapted to make engagement when in its upper position with the contact 76 provided upon a leaf spring 78. The outer end of the leaf spring 78 is provided with a button 80 which is adapted to normally engage the stop 82 for limiting the downward movement of the contact 76. By this arrangement a definite voltage will be maintained upon the heater 50 by alternately energizing and shunting the resistance 54 to control the voltage and the current passing through the heater 50.

In Fig. 3 there is shown another system which includes a battery 128 and a solenoid switch 122 for connecting the starting motor 120 to the terminals of the battery 128. The solenoid switch 122 is provided with the solenoid operating coil 124 under the control of suitable switches such as a pressure switch 138 and a temperature switch 142. The closing of both of these switches is required to close the switch 122 for energizing the starting motor of the internal combustion engine.

In order to stop the starting motor 120 after a predetermined period of time, such as 30 seconds, I provide a bimetal timing device including a cantilever supported bimetal member 146 which is controlled by a compression type snap acting spring 147. This bimetal 146 is connected to one terminal of the battery 128 while its free end is provided with contact means for making

contact at one end of its movement with the contact 144 connected in series with the switches 138 and 142 as well as the solenoid 124.

The bimetal 146 is provided with an electric heater 150 having uniform current flowing through it regardless of the condition of the battery 128. This is insured by an electromagnetic vibrating control which includes a solenoid 156 connected in series with the heater 150. This solenoid 156 operates upon an armature 158 which, in the open position, connects to a conductor 160 shunting the resistance 154 which is otherwise connected in series with the solenoid 156 and the heater 150.

As explained in connection with Figs. 1 and 2 this vibrating type control 156 regulates the current passing through the heater 150 by the energizing and shunting of the resistance 154 through the operation of the electromagnetic vibrating device. However, in the form shown in Fig. 3, the solenoid 156 is connected in series with the heater 150 instead of in parallel as in Fig. 1. If the internal combustion engine should fail to start within the prescribed time, the heater 150 will heat the bimetal 146 sufficiently to cause the contacts at the end of the bimetal 146 to be moved with a snap action into contact with the stationary contact 151, connecting with the signaling device 152, such as a buzzer. This will indicate the failure of the engine to start. This device requires a manual reset and for this purpose I have provided a push button 165 which may be pushed downwardly to return the bimetal 146 to the position shown in Fig. 3 so that the engine can again be started. This device may also be used in the form shown in Fig. 1 replacing the bimetal 46, the rod 48, and the switch 44. As described in connection with Fig. 1, the failure of the electromagnetic vibrating contact device by the sticking of the contacts will only serve to shorten the time the starting motor is allowed to operate. Thus the starting motor is always protected. The electromagnetic vibrating contact device accurately controls the flow of current through the heater 150, so that the time the starting motor is allowed to operate in case the engine fails to start is always accurately determined regardless of the condition of the battery 128. The system can be made to withstand rough usage and may be used on any sort of vehicle or almost any stationary application.

While the form of embodiment of the invention as herein disclosed, constitutes a preferred form, it is to be understood that other forms might be adopted, all coming within the scope of the claims which follow.

What is claimed is as follows:

1. A starting system for an internal combustion engine comprising an electric starting motor for cranking purposes, a switch means for controlling the energization of the starting motor, an electrical timing device for deenergizing the motor after a certain amount of cranking, a solenoid energized in proportion to the current flowing through said timing device, a resistance connected in series circuit relation with said solenoid and timing device, and a set of vibrating contacts operated by said solenoid for intermittently shunting said resistance to regulate the energization of the timing device.

2. A starting system for an internal combustion engine comprising an electric starting motor for cranking purposes, a switch means for controlling the energization of the starting motor, an electrothermal timing device for deenergiz-

ing the motor after a certain amount of cranking, a solenoid energized in proportion to the current flowing through said timing device, a resistance connected in series circuit relation with said solenoid and timing device, a set of vibrating contacts operated by said solenoid for intermittently shunting said resistance to regulate the energization of the timing device, and means controlled by said timing device for indicating the deenergization of said starting motor by said switch means.

3. A starting system for an internal combustion engine comprising an electric starting motor for cranking purposes, an electrically operated switch means for controlling the energization of the starting motor, an electrical timing device for operating said electrically operated switch means after a certain amount of cranking, a solenoid energized in proportion to the current flowing through said timing device, a resistance connected in series circuit relation with said sole-

noid and timing device, and a set of vibrating contacts operated by said solenoid for intermittently shunting said resistance to regulate the energization of the timing device.

- 5 4. A starting system for an internal combustion engine comprising an electric starting motor for cranking purposes, an electrically operated switch means for controlling the energization of the starting motor, an electrical timing device for operating said electrically operated switch means after a certain amount of cranking, a solenoid energized in proportion to the current flowing through said timing device, a resistance connected in series circuit relation with said solenoid and timing device, a set of vibrating contacts operated by said solenoid for intermittently shunting said resistance to regulate the energization of the timing device, and means controlled by said timing device for indicating the deenergization of said starting motor by said switch means.
- 10 15 20
- 15 4. A starting system for an internal combustion engine comprising an electric starting motor for cranking purposes, an electrically operated switch means for controlling the energization of the starting motor, an electrical timing device for operating said electrically operated switch means after a certain amount of cranking, a solenoid energized in proportion to the current flowing through said timing device, a resistance connected in series circuit relation with said solenoid and timing device, a set of vibrating contacts operated by said solenoid for intermittently shunting said resistance to regulate the energization of the timing device, and a second switch means for controlling the energization of said electrically operated switch means.

ALBERT J. KUHN.
